Design U.S. Appl. No. 29/508,541, filed Nov. 7, 2014, entitled "Pool Cleaner" (8 pages).

(Continued)

Primary Examiner — Ruth McInroy*(74) Attorney, Agent, or Firm* — McCarter & English, LLP(57) **CLAIM**

We claim the ornamental design for a pool cleaner, as shown and described.

DESCRIPTION

FIG. 1 is a front perspective view of a pool cleaner; FIG. 2 is a rear perspective view of the pool cleaner of FIG. 1;

FIG. 3 is a front elevational view of the pool cleaner of FIG. 1;

FIG. 4 is a rear elevational view of the pool cleaner of FIG. 1;

FIG. 5 is a right side elevational view of the pool cleaner of FIG. 1, a left side elevational view being a mirror image thereof; and,

FIG. 6 is a top plan view of the pool cleaner of FIG. 1. ps The details shown in broken lines form no part of the claimed design.
